CLAIM

The ornamental design for a combined digital audio disc player and radio tuner for a vehicle, as shown and described.

DESCRIPTION

FIG. 1 is a front perspective view of a combined digital audio disc player and radio tuner for a vehicle showing our new design;

FIG. 2 is a front view thereof;

FIG. 3 is a left side elevational view thereof;

FIG. 4 is a right side elevational view thereof;

FIG. 5 is a top plan view thereof; and,

FIG. 6 is a bottom plan view thereof.

The broken line showing in FIGS. 1 and 3-6 is for illustrative purposes only and forms no part of the claimed design.
